DESIGN FOR A LIFTING HANDLE FOR WAFFLE BAKER OR THE LIKE

Jean O. Reinecke and James F. Barnes, Chicago,
Ill., assignors to McGraw Electric Company,
Elgin, Ill., a corporation of Delaware

Application August 10, 1939, Serial No. 86,591

Term of patent 7 years

To all whom it may concern:

Be it known that we, Jean O. Reinecke and James F. Barnes, citizens of the United States, both residing at Chicago, in the county of Cook and State of Illinois, have invented a new, original, and ornamental Design for a Lifting Handle for Waffle Baker or the like, of which the following is a specification, reference being had to the accompanying drawing, forming part thereof, in which:

Fig. 1 is a top plan view of a lifting handle for waffle baker or the like, showing our new design; and

Fig. 2 is a front elevational view thereof.

We claim:

The ornamental design for a lifting handle for waffle baker or the like, substantially as shown.

JEAN O. REINECKE.
JAMES F. BARNES.
